UNITED STATES PATENT OFFICE

2,460,758

LOCKOUT AND ALARM DEVICE FOR
CIRCUIT BREAKERSHarold H. Lawson, Philadelphia, Pa., assignor to
General Electric Company, a corporation of
New York

Application March 23, 1946, Serial No. 656,568

5 Claims. (Cl. 177—311)

1

My invention relates to improvements in lockout and alarm devices for circuit breakers and more particularly for circuit breakers which are provided with automatic tripping means for effecting their opening under abnormal conditions.

Circuit breakers have been provided with alarm switches so arranged as to effect the ringing of a bell, the lighting of a lamp, the operation of an annunciator drop and the like when tripped automatically. The arrangements with which I am familiar, however, are unsatisfactory. The addition of a manually operated cutoff switch in the alarm circuit to open it without reclosing the circuit breaker is unsatisfactory because, if an operator upon reclosing a circuit breaker, failed to restore the manually operated switch at the same time to correspond to the circuit breaker closed position, then an erroneous indication would be presented. This discrepancy between the circuit breaker closed position and alarm indication of circuit breaker open position might readily result in damage to both apparatus and personnel. Also, with either of the foregoing arrangements, an alarm is given whether the circuit breaker is tripped automatically or manually. Moreover, arrangements with which I am familiar are not economical because of the amount of wiring and other features involved.

An object of my invention is to provide an improved lockout and alarm device for circuit breakers so that after being automatically tripped the circuit breaker cannot be reclosed before the alarm indication of circuit breaker open position is cleared. Another object of my invention is to provide an improved lockout and alarm device which is relatively simple in structure and operation and which will selectively differentiate between automatic tripping and manual tripping of the circuit breaker. Still another object of my invention is to provide an improved lockout and alarm device which is readily adaptable to various circuit breakers and especially the tripping means associated therewith. A further object of my invention is to provide an improved automatic circuit breaker lockout and alarm device which is particularly adapted for manually resetting without any possibility of blocking or interfering with the operation or calibrating of the automatic tripping mechanism of the circuit breaker. These and other objects of my invention will appear in more detail hereinafter.

In accordance with my invention, I provide in a manually reset lockout and alarm device for a circuit breaker provided with a tripping element and automatic actuating means therefor, means

2

for maintaining the tripping element in the tripped position only when operated thereto by the automatic tripping means in consequence of the operation thereof. For this purpose, I provide a lockout member biased for movement from an initial position to a final position into holding engagement with the circuit breaker tripping element to prevent reclosing of the circuit breaker only after it has been automatically tripped. To permit reclosing of the circuit breaker, I provide manual actuating means adapted to be operated to return the lockout member against the bias thereon to the initial position and means including a latch for holding the lockout member in the initial position and arranged to be released only upon operation of the circuit breaker automatic tripping means whereby to effect movement of the lockout means to its final position. Also in accordance with my invention, I provide the lockout member with alarm means to provide an indication of the automatic tripping of the circuit breaker.

My invention will be better understood from the following description when considered in connection with the accompanying drawing, and its scope will be pointed out in the appended claims.

In the accompanying drawing, Fig. 1 is a side elevation illustrating an embodiment of my invention as applied to a circuit breaker, shown only in part, with the parts presented in the circuit breaker closed position, and Fig. 2 is a side elevation similar to Fig. 1 with the parts presented at the moment of tripping the circuit breaker.

For the purpose of illustrating my invention, I have shown an embodiment thereof as applied to a circuit breaker secured to a base 1 of insulating material and shown only in part as comprising a supporting frame 2. As far as my invention is concerned, the particular type of circuit breaker is immaterial, but I have further illustrated the circuit breaker as including a tripping mechanism comprising a tripping shaft or element 3 which is supported in the frame 2 and is provided with a tripping arm 4. The shaft 3 is biased to the holding position shown in Fig. 1 by a spring 5. For actuating the tripping shaft 3 to the releasing position, the circuit breaker is also shown as provided with automatic electro-responsive actuating means comprising a U-shaped magnet 6, an energizing winding 7 and an armature 8. The magnet 6 is secured to the base 1 by suitable means such as screws 9. For current response, the winding 7 is connected between the lower stud 10 of the circuit breaker and the lower contact block 11 so as to be in

series relation with the circuit through the circuit breaker. The armature 8 is pivotally supported at 12 in a bracket 13 which is shown as secured to the magnet 6 and to a supporting bracket 14 suitably secured to the circuit breaker frame 2. Also the armature 8 is biased to the unattracted position by suitable means, not shown, which may be adjusted, as well known to the art, for controlling the pickup point or response of the tripping means. For actuating the tripping shaft 3 to the tripping or releasing position upon movement of the armature 8 from the unattracted position shown in Fig. 1 to the attracted position shown in Fig. 2, the armature is provided with a hook-shaped extension 15 which is arranged to engage the lower end of a tripping lever 16 pivotally mounted at 17 in a bracket 18 secured to the circuit breaker frame 2. The lever 16 is provided with a curved upper portion 19 which is arranged upon clockwise movement of the lever 16 to engage the tripping arm 4 and to turn it counterclockwise to the releasing position shown in Fig. 2. For adjustment purposes, a screw 20 is mounted in the bracket 18 for contact with the lever 16 to establish its non-tripped position shown in Fig. 1.

In accordance with my invention, I provide means for maintaining the circuit breaker tripping shaft or element 3 in the tripped position, shown in Fig. 3, after actuation thereto in consequence of the operation of the electro-responsive tripping means. As shown, this means is a lockout member 21 which is mounted for movement from an initial position, shown in Fig. 1, to a final position, shown in Fig. 2, into holding engagement with the tripping shaft 3 through the medium of an arm 22 suitably secured thereto as by a bolt 23. Also, in accordance with my invention, the lockout member 21 functions as an alarm control or switching member and is mounted for rectilinear movement in a suitably shaped block 24 of insulating material secured to the supporting bracket 14 as by a bolt 25. The member 21 is biased to the trip element holding or final position by suitable means such as a spring 26 which, as shown, is around the member between the top of the block 24 and nuts 27 on the member for adjustment purposes. In the trip element holding position, the member 21 is also arranged to complete the circuit 28 of suitable alarm and indicating devices such as a bell 29 and a lamp 30. For this purpose, the member 21 is arranged to actuate suitable contact means such as a movable contact 31, which, as shown, is resiliently supported on the member and is arranged to bridge stationary contacts 32 mounted on the block 24 and provided with terminals 33 to which the circuit conductors 28 are connected. For energizing the alarm circuit 28, a suitable source of electro-motive force such as a battery 34 is provided.

Further in accordance with my invention, I provide actuating means adapted to be operated to return the lockout member 21 to the initial position shown in Fig. 1 against the bias of the spring 26 so that the tripping shaft 3 may return to the latching position shown in Fig. 1 under the bias of the spring 5. As shown, this actuating means comprises an element 35 which is connected to the lockout member 21 for movement simultaneously therewith and relatively thereto and is movable in one direction to return the member to its initial position. For this purpose, the actuating or resetting element 35, which is roughly U-shaped, is pivoted at 36 on

5 the supporting bracket 14 and is also loosely pivotally connected to the member 21 by a pin 37 on the member and projecting into a slot 38 in the element so that it can have freedom of angular movement without interfering with the linear movement of the member.

For actuating the element 35 is a direction, clockwise as viewed in the drawing, to return the lockout member 21 to its initial position, I provide means such as a push rod 39 which, as shown, is linearly movable from right to left as viewed in Fig. 2 to engage the leg 40 of the resetting element 35 and turn it clockwise about its pivot 36. As shown, the push rod 39 is mounted on the supporting bracket 14 and biased for movement from left to right away from the element 35 by suitable means such as a spring 41. For ease in manipulation, the push rod 39 is provided with a knob or handle 42.

For holding the resetting element 35 in a position to maintain the lockout member 21 in its initial position, I provide means which is arranged to be released upon operation of the electroresponsive tripping means whereby to effect movement of the member to its final or trip holding position under the action of the spring 26. For this purpose, I provide a latch 43 which, as shown, is mounted on a shaft 44 arranged to turn about the same pivotal axis 12 as the armature 8 does and to engage the leg 45 of the actuating element 35 as shown in Fig. 1. On the shaft 44, there is mounted a lever 46 having an arm 47 extending outwardly from the plane of the drawing into the path of movement of the armature 8 so that upon movement thereof to the attracted position, the latch 43 is released to permit movement of the element 35 and the member 21 under the bias of the spring 26. For resetting the latch 43 to the holding position, it may be biased by suitable means such as a spring 48 attached to the arm 46 and to the supporting bracket 14. Also, I have shown the shaft 44 as provided with a counterbalancing weight 49 which tends to turn the shaft counterclockwise and to render it less susceptible to movement from shocks. For establishing the desired latching, I provide an adjustable stop 50 which, as shown, is mounted on the supporting bracket 14 in the path of movement of the arm 46.

Assuming now the parts positioned as shown in Fig. 1 and that the circuit breaker is closed, then the resetting element 35 is maintained in the holding position against the bias of the spring 26 by the latch 43. When current flows in the winding 7 to an amount sufficient to attract the armature 8, the tripping lever 16 will be engaged by the hook-shaped extension 15 on the armature and turned clockwise sufficiently to rotate the tripping arm 4 to the releasing position against the bias of the spring 5. Substantially simultaneously therewith, the latch 43 is released from the arm 45 of the resetting member 35 so that the lockout and operating member 21 is free to move upwardly under the bias of the spring 26 from the initial position shown in Fig. 1 to the trip holding position shown in Fig. 2. At the same time, the bridging contact 31 engages the stationary contacts 32 to complete the alarm circuit 28 thereby lighting the lamp 30 and ringing the bell 29, if both of these devices are provided. As long as the lockout and alarm member 21 remains in the trip holding position in engagement with the arm 22 on the trip shaft 3, the circuit breaker cannot be re-

closed because the trip shaft is held in a position such that it cannot be moved to the circuit breaker mechanism holding position. Before the circuit breaker can be closed, the actuating element 35 must be rotated clockwise so that the latch 43 can fall in behind the end of the arm 45. This clockwise movement of the actuating element 35 is effected by pushing in on the knob 42 to engage the arm 40 so that it can be rotated sufficiently to come into the latching position, as shown in Fig. 1. With this arrangement, it will be obvious that before the circuit breaker can be reclosed the alarm indication, showing that the circuit is open after an automatic tripping, must be annulled.

From the foregoing, it will be apparent to those skilled in the art that devices, embodying my invention, may be used on single pole or multi-pole circuit breakers wherein all poles open when one pole is tripped and only one device is necessary to accomplish the desired results where all poles trip. Moreover, as far as my invention is concerned, it is immaterial whether the automatic tripping means is electroresponsive, such as the overcurrent device illustrated, or is pressure or float operated or the like.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. A manually reset lockout and alarm device for a circuit breaker trip mechanism having automatic tripping means, comprising an auxiliary latch released by said automatic tripping means, lockout means including a member held under control of said latch in an inactive position and having biasing means for moving said member therefrom upon release of said latch to a lockout position for holding said mechanism to prevent reclosure of the circuit breaker, alarm switching means operated by said member in said lockout position, and manual reset means for returning said member to said inactive position.

2. In a circuit breaker trip control and alarm mechanism, a circuit breaker trip member having a tripping position for opening the circuit breaker and preventing reclosure thereof, biasing means for biasing said trip member to an inactive position, automatic tripping means for moving said member to the tripping position, a lockout member having biasing means for moving said lockout member to a lockout position for holding said trip member in said tripping position thereof to prevent reclosure of the circuit breaker, alarm switching means operated by said member in said lockout position thereof, a latch for holding said lockout member in an inactive position, means under control of said automatic tripping means for releasing said latch, and manual reset means for returning the lockout member to said inactive position.

3. In a circuit breaker trip control and alarm mechanism, a circuit breaker trip shaft rotatable

to a tripping position for opening the circuit breaker and preventing reclosure thereof, biasing means for biasing said trip shaft to an inactive position, automatic tripping means for rotating said shaft to said tripping position, an arm on said shaft, a movable lockout member having biasing means for moving said lockout member to a lockout position in engagement with said arm to hold the shaft in said tripping position and thereby prevent reclosure of the circuit breaker, alarm switching means operated by said member in said lockout position thereof, a latch for holding said lockout member in an inactive position, means under control of said automatic tripping means for releasing said latch, and manual reset means for returning the lockout member to said inactive position.

4. In a manually reset lockout and alarm device for a circuit breaker having a tripping shaft and automatic actuating means therefor, an arm on said shaft, a member having biasing means for moving said member from an inactive position to a position for holding said arm in the tripped position of said shaft, alarm switching means operated by said member in the holding position thereof, control means for said member including a pivotally mounted element connected with said member for pivotal movement upon movement of said member between said positions, manual reset means for operating said pivotal element to return the member to the inactive position and a latch for engaging said pivoted element to maintain said member in its inactive position, said latch having a member operated by said automatic actuating means only upon operation thereof to trip the breaker for releasing said latch to effect movement of the biased member to said holding position.

5. In a manually reset lockout and alarm device for a circuit breaker provided with a trip shaft having two arms thereon and automatic actuating means for one of said arms, a member having biasing means for moving said member from an inactive position to a position for engaging the other arm to hold the trip shaft in the tripped position, alarm switching means operated by the member in the holding position thereof, manual reset means including a pivotally mounted element connected with said member to return the member to its inactive position, a latch biased into engagement with said pivoted member to hold said member in its inactive position, and a member operated by said automatic actuating means for releasing said latch upon operation of the trip shaft to the tripped position.
